NEW JERSEY

SHEET HANDLING MECHANISM

Application filed July 22, 1929. Serial No. 380,046.

This invention relates to sheet piling mechanism and, while not limited thereto, relates particularly to means for piling cold rolled metal sheets, and has for one of its objects the provision of means for edging the sheets as they are piled so as to form an accurate pile and eliminate protruding edges which would be burned during annealing of the piled sheets.

10 Another object is to provide a piling mechanism that may be adjusted to pile various sizes of sheets.

In the drawings:

Figure 1 is a plan view of a piling apparatus embodying our invention.

Figure 2 is a side elevation thereof.

Figure 3 is a sectional elevation taken on the line III—III of Figure 1.

Figure 4 is a sectional elevation taken on the line IV—IV of Figure 2.

Referring more particularly to the drawings, the numeral 2 designates a belt conveyer which delivers a succession of rolled sheets A into the bite of a pair of concave and convex feed-rollers 3, which rollers feed the sheets into the piling mechanism (to be described) and onto an annealing base B.

The belt conveyer 2 is trained over suitable head pulleys 4 mounted on a head shaft 5 which is journaled in suitable bearings in a supporting frame 6. The feed-rollers 3 are also journaled in the frame 6.

A pair of supporting shafts or bars 7 and 8 are secured in the frame 6 and a screw adjusting bar 9 is journaled in the frame 6 between the bars 7 and 8.

A stationary side guide-plate 10 is carried by the bars 7 and 8 and an L-shaped guide-carrying frame 12 is slidably mounted on the bars 7 and 8 and has a threaded engagement with the screw-bar 9 so that it may be adjusted toward and away from the stationary side guide-plate 10 by rotating the screw-bar 9.

45 A normally stationary end guide-plate 14 having a stem 15 is adjustably secured in a sleeve 16 on the frame 12 and is locked in position by a set-screw 17.

The head shaft 5 is a driven shaft and is provided with a sprocket 18 which is con-

nected to a sprocket 19 on the lower feed-roller shaft 20 by a chain 21.

A plurality of side guide fingers 22 are hingedly or pivotally mounted on and depend from the frame 12, as at 22^a.

55 A slide bar 23 is mounted for reciprocatory movement in bearings 24 on the frame 12. Suitable bell-crank levers 25 are pivotally mounted on the frame 12 and have one end pivotally connected to said slide bar and their other ends connected by links 26 to respective ones of said guide fingers 22 so that reciprocatory movement of said slide bar will cause a swinging movement of said fingers.

The bar 23 is reciprocated by means of a 65 crank-gear 27 which is meshed with an elongated gear 28 formed on the lower or driven roller of the feed-rollers 3. The gear 27 is carried by a bracket 29 on the frame 12 and has an eccentric connection with a connecting rod 30 which is connected to an arm 31 on the bar 23. The gear 27 is adapted to slide along the gear 28 when the frame 12 is adjusted transversely or toward or away from the stationary guide-plate 10.

70 A plurality of end guide fingers 32 are hingedly mounted in bearings 33 opposite the stationary end guide-plate 14. A gear 34 is keyed to the head shaft 5 and a crank-gear 35 is meshed therewith. A connecting rod 36 has one end eccentrically connected with the crank-gear 35 and its other end is connected with a crank-arm 37 on a shaft 38. Suitable crank-arms 39 are secured to the shaft 38 and are connected to the respective 75 end guide fingers 32 by links 40 so that oscillation of the shaft 38 will cause the fingers 32 to swing or move toward and away from the stationary guide-plate 14.

80 In operation, the sheets A are fed through the rollers 3 and, due to the shape of the rollers 3, the sheets will be curved transversely so as to render them stiff and cause them to be fed into the piling mechanism in a horizontal plane. The sheets A will be fed into the piling mechanism with enough force to cause them to engage the end guide-plate or stop 14. The swinging side guide fingers 22 and the end guide fingers 32 will be constantly moving in and out while the sheets are 85 90 95 100

being piled and consequently will impart a succession of blows to the sheets as they settle between the guides, thus forcing said sheets in against the stationary guide-plates 10 and 14 which form a right angle.

In addition to edging the sheets the guide fingers 22 and 32, due to their movement, serve to provide increased clearance between the guides when they swing outwardly so as 10 to permit unrestricted fall of the sheets, thus facilitating the settling of the sheets.

While we have shown and described one specific embodiment of our invention it will be understood that we do not wish to be 15 limited thereto, since various modifications in constructional details may be made without departing from the scope thereof, as defined in the appended claims.

We claim:

- 20 1. A sheet piling mechanism comprising in combination a pair of supporting bars, a stationary side guide member mounted on said bars, an L-shaped guide-carrying frame slidably mounted on said bars for movement toward and away from said stationary side guide member, means for moving said frame on said bars, a normally stationary end guide-plate carried by said frame and adjustable toward and away from said frame, a plurality of side guide fingers hingedly mounted on said frame so as to depend therefrom opposite said stationary side guide member, bearings on said frame, a slide bar mounted for reciprocatory movement in said bearings, bell-crank levers pivotally mounted intermediate their ends on said frame, said levers having one end pivotally connected to said slide bar and their other connected by links to respective ones of said guide fingers, and power means for reciprocating said slide bar to cause a swinging movement of said side guide fingers.
- 25 2. A sheet piling mechanism comprising in combination a pair of supporting bars, a stationary side guide member mounted on said bars, an L-shaped guide-carrying frame slidably mounted on said bars for movement toward and away from said stationary side guide member, means for moving said frame on said bars, a normally stationary end guide-plate carried by said frame and adjustable toward and away from said frame, a plurality of side guide fingers hingedly mounted on said frame so as to depend therefrom opposite said stationary side guide member, bearings on said frame, a slide bar mounted for reciprocatory movement in said bearings, bell-crank levers pivotally mounted intermediate their ends on said frame, said levers having one end pivotally connected to said slide bar and their other connected by links to respective ones of said guide fingers, power means for reciprocating said slide bar to cause a swinging movement of said side guide fingers, end guide fingers mounted for swinging movement opposite said stationary end guide-plate, and means for swinging 105 said end guide fingers toward and away from said end guide-plate.
- 30 3. A sheet piling mechanism comprising in combination a pair of supporting bars, a stationary side guide member mounted on said bars, an L-shaped guide-carrying frame slidably mounted on said bars for movement toward and away from said stationary side guide member, means for moving said frame on said bars, a normally stationary end guide-plate carried by said frame and adjustable toward and away from said frame, a plurality of side guide fingers hingedly mounted on said frame so as to depend therefrom opposite said stationary side guide member, end guide fingers mounted opposite said end guide-plate for swinging movement toward and away from said plate, and means for swinging 110 said side and end guide fingers.
- 35 4. In a sheet piling mechanism a pair of supporting bars, a stationary side guide

member mounted on said bars, an L-shaped guide-carrying frame slidably mounted on said bars for movement toward and away from said stationary side guide member, means for moving said frame on said bars, a normally stationary end guide-plate carried by said frame and adjustable toward and away from said frame, a plurality of side guide fingers hingedly mounted on said frame so as to depend therefrom opposite said stationary side guide member, bearings on said frame, a slide bar mounted for reciprocatory movement in said bearings, bell-crank levers pivotally mounted intermediate their ends on said frame, said levers having one end pivotally connected to said slide bar and their other connected by links to respective ones of said guide fingers, and power means for reciprocating said slide bar to cause a swinging movement of said side guide fingers.

In testimony whereof, we have hereunto set our hands,

JAMES K. LAMOREE.

ARCHIBALD D. EVANS.
